UNITED STATES PATENT OFFICE.

CHRISTIAN WILLIAM MEINECKE, OF JERSEY CITY, NEW JERSEY.

DESIGN FOR A SYRINGE.

SPECIFICATION forming part of Design No. 31,033, dated June 20, 1899.

Application filed May 25, 1899. Serial No. 718,294. Term of patent 14 years.

To all whom it may concern:

Be it known that I, CHRISTIAN WILLIAM MEINECKE, a citizen of the United States, residing at Jersey City, in the county of Hudson and State of New Jersey, have invented and produced a new and original Design for a Syringe, of which the following is a specification.

This design relates to the class of syringes known as "infants' rectal syringes;" and the feature of the design consists in a soft-rubber bulb of curved outline in cross-section and having a cross-line, an upper bone shield, and a hard-rubber nozzle, as set forth in the following specification and claim and illustrated in the annexed drawing, showing a perspective view of the syringe.

The soft-rubber bulb is shown with its side

1 curved in cross-section and having a cross line or bead 2 extending about the bulb, giving a belt or zone like appearance. The bulb has a bone shield 4 at its upper part. Above the shield is a hard-rubber pipe or nozzle 5.

The design presents a novel, striking, and characteristic appearance.

What I claim as new, and desire to secure by Letters Patent, is—

The design for a syringe substantially as shown and described.

In testimony whereof I have hereunto set my hand in the presence of two subscribing witnesses.

CHRISTIAN WILLIAM MEINECKE.
